UNITED STATES PATENT OFFICE

MICHAEL REISCH, OF BUFFALO, NEW YORK.

JACK-SCREW.

SPECIFICATION forming part of Letters Patent No. 364,373, dated June 7, 1887.

Application filed December 6, 1886. Serial No. 290,790. (No model.)

To all whom it may concern:

Be it known that I, MICHAEL REISCH, a citizen of the United States, residing at Buffalo, in the county of Erie and State of New York, have invented certain new and useful Improvements in Jack-Screws; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of my invention is to provide a jack-screw by means of which, with the same motion of the operating-lever, a body can be raised or lowered twice the distance traveled by the body when operated upon by the ordinary jack-screw.

To that end my invention consists of a certain improved construction and arrangement of parts, all of which will be more fully hereinafter described and claimed.

In the drawings, Figure 1 is a central vertical section of my improved jack. Figs. 2 and 3 are detached plan views of the oscillating catches and ratchet-wheels, showing their plan of operation. Figs. 4 and 5 are an elevation and plan, respectively, of the flanged collar. Figs. 6 and 7 are detached detail views, and Fig. 8 is a modification.

Referring to the drawings, *a* is the tubular standard having the base *a'*. Its top is provided with the screw-threaded aperture *a''*. Diametrically arranged upon the inner wall of the tubular standard *a* are the two vertical ribs *a³* *a⁴*.

b is a screw-threaded cylinder, having upon its upper end and integral therewith the ratchet-wheel *b'*. This cylinder *b* is adapted for engagement with the screw-threaded aperture *a''* of the standard *a*, in which it is to be raised and lowered.

c is a tubular collar with the annular flange *c'* at its top, and the keeper *c''* with grooves *c³* *c⁴* on either side. This collar fits loosely within the cylinder *b*, its annular flange *c'* resting upon the top of the ratchet-wheel *b'* of the cylinder *b*, and the grooves *c³* *c⁴* of the keeper *c''* loosely engaging with the vertical ribs *a³* *a⁴* of the standard *a* to keep it from turning.

c'' is a lug upon the inner wall of the collar *c*. *d* is a screw-threaded rod operating within the tubular collar *c*, at the top of which is rigidly secured the notched circular plate *d'*, which forms the top of the jack. Along the side of the screw-threaded rod *d* is the vertical groove *d''*, adapted for the reception of the lug *c''* in the collar *c*.

e is a ratchet-wheel in engagement with the screw-threaded rod *d* just over the annular flange *c'* of the collar *c*. A casing, *f*, incloses the ratchet-wheels *b'* and *c*, at the outer end of which is the lever-handle *f'*.

The rod *d* passes loosely out of the top of the casing *f*, and the screw-threaded cylinder *b* extends loosely through the lower wall of the same casing. At one side of the casing in its lower portion is pivoted the oscillating plate *g*, having the two pawls *g'* *g''* and the lug *g³*. The pawls *g'* *g''* are adapted for engagement alternately with the ratchet-wheel *b'*, being held in either of such positions by the spring-pressed catch *h*, as clearly seen in Fig. 3. *k* is a similar oscillating plate, having pawls *k'* *k''* and lug *k³*, with spring-pressed catch *k⁴*. The pawls *k'* *k''* are adapted for engagement alternately with the ratchet-wheel *c*. The operation of the parts just described is as follows:

To raise the notched plate *d'*, and with it the body placed upon it, the left-hand pawl, *g'*, of the plate *g* is placed in engagement with the ratchet-wheel *b'*, as seen in Fig. 3, and the right-hand pawl, *k'*, of the plate *k* is placed in engagement with the ratchet-wheel *c*, as seen in Fig. 2, both pawls being held in place by the spring-catches *h* and *k⁴*. As the lever-handle *f'* is turned to the right, and with it the casing *f*, the ratchet-wheel *c* is turned to the right also by the pawl *k'*, and as the screw-threaded rod passing through the ratchet-wheel cannot turn, by reason of the lug *c''*, it rises in such ratchet-wheel, carrying with it the object placed upon the notched plate *d'*. As the lever-handle *f'* is thrown back to the left, the ratchet-wheel *b'* upon the screw-threaded cylinder *b* is turned by the pawl *g'*, which causes the cylinder to turn in its screw-threaded socket *a''* in the standard *a*, and at the same time to rise, carrying with it the upper parts of the jack and the object to be lifted thereby. The annular flange *c'* of the collar

c, being interposed between the ratchet-wheels, prevents one wheel from moving the other in their raising or lowering action, the collar and its shoulder having only a vertical movement with the other parts. It will thus be seen that by my improved construction the object to be raised or lowered is moved a certain distance for each movement of the lever-handle in either direction.

10 To lower the object, the opposite pawls of each oscillating plate are engaged with the ratchet-wheels, and as they then operate in the opposite directions the moving of the lever-handle serves to lower the rod *d* and cylinder *b* in the same manner as they were before raised.

15 In Fig. 2 I show a pivoted oscillating plate, *m*, having the two hooks *m'* *m''* adapted for alternate engagement with the ratchet-wheel *e*, their functions being to hold the ratchet-wheel *e* and prevent its rotary movement when the lever-handle *f'* is moved, thus throwing the entire lifting of the jack upon the other ratchet-wheel, *b'*, when desired. A spring-pressed catch, *m'*, (see Fig. 1,) serves, in connection with a lug or plate, *m*, to hold such plate in either of its positions.

20 In Fig. 8 I have shown a modification of the form already described, in which *n* and *o* are hollow tubes or cylinders, the cylinder *n* forming, with its enlarged lower portion, *n'*, the base of the jack, and the cylinder *o*, with its upper serrated edge, *o'*, forming the bearing-piece for the object to be raised. Each of the cylinders *n* and *o* is provided with the screw-threaded apertures *n''* and *o''*, and each has the interior vertical ribs *n''* *n'''* and *o''* *o'''*, arranged diametrically opposite each other. *p* and *q* are exteriorly screw-threaded tubes, engaging with the screw-threaded apertures *n''* and *o''* of the tubes *n* and *o*. At the adjacent ends of these tubes *p* and *q*, and integral therewith, are the ratchet-wheels *p'* and *q'*.

25 Passing through the tubes *p* and *q* is the rod *r*, having the central washer, *r'*, which lies between and separates the ratchet-wheels *p'* and *q'*. The keepers *r''* and *r'''*, secured to the rod *r* at each end by the nuts *r''*, engage with the vertical ribs *n''* *n'''* and *o''* *o'''* to keep the rod from turning.

30 The ratchet-wheels *p'* and *q'* and washer *r'* are inclosed in a casing, *s*, similar to the casing *f* in Fig. 1, which casing *s* has a lever-handle, *s'*, attached thereto. The ratchet-wheels *p'* and *q'* are operated within the casing by pawls and spring-catches similar to those shown in Figs. 2 and 3, and the operation of the jack just de-

scribed is substantially the same as the one first described, in that it raises the body a certain distance for each motion of the lever-handle *s'*, and lowers such object in the same manner.

I claim—

1. A lifting-jack having substantially two lifting-screws, separate and independent of each other, each screw having an independent ratchet-wheel operated by a separate pawl, the ratchet-wheels and their pawls being inclosed in a common casing provided with a single lever-handle, the movement of which operates one of the ratchet-wheels in each direction, all combined substantially as shown and described.

2. In a lifting-jack, the combination, with the screw-threaded cylinder *b*, having integral ratchet-wheel *b'*, adapted to be moved up and down in the tubular standard *a*, the screw-threaded rod *d*, adapted to be moved up and down in the ratchet-wheel *e*, engaged therewith, and the tubular collar *c*, having the annular shoulder *c'* between the ratchet-wheels *b'* and *e*, and having a keeper at its lower end engaging with vertical ribs in the hollow standard *a*, of the double spring-pressed catches and plates *h* and *g*, engaging independently with each ratchet-wheel, the pawls and ratchet-wheels being inclosed in a common casing and operated by a single lever-handle secured to the casing, substantially as shown and described.

3. In a lifting-jack, the combination, with the screw-threaded cylinder *b*, having integral ratchet-wheel *b'*, and adapted to be moved up and down in the tubular standard *a*, the screw-threaded rod *d*, adapted to be moved up and down in the ratchet-wheel *e*, engaged therewith, and the tubular collar *c*, having the annular shoulder *c'* between the ratchet-wheels *b'* and *e*, and having a keeper at its lower end engaging with vertical ribs in the hollow standard *a*, of the double spring-pressed catches and plates *h* and *g*, engaging independently with each ratchet-wheel, and the double-hooked plates *m* *m'* *m''*, for the purpose stated, the pawls, ratchet-wheels, and hooks being inclosed in a common casing and operated by a single lever-handle secured to the casing, substantially as shown and described.

In testimony whereof I have signed my name to this specification in the presence of two subscribing witnesses.

MICHAEL REISCH.
